UNITED STATES PATENT OFFICE.

FRANK H. LEHMAN, OF LEBANON, PENNSYLVANIA.

ASH-SIFTING DEVICE.

Application filed September 21, 1921. Serial No. 502,161.

To all whom it may concern:

Be it known that I, FRANK H. LEHMAN, a citizen of the United States, residing in the city of Lebanon, county of Lebanon, and State of Pennsylvania, have invented certain new and useful Improvements in Ash-Sifting Devices, of which the following is a specification.

The present invention relates to improvements in ash sifting devices, and more especially to those adapted to be used in the household for sifting ashes drawn from stoves and furnaces; and the invention has for its principal object the production of a cheap, improved, novel and dustless sifter of this kind designed to render available for employment in cooperative relationship, an ash can of the conventional cylindrical type, a lid therefor, and a common pail.

Another object of the invention is the employment in an ash sifter of means, devices and mechanism adapted for sifting ashes on a novel principle, involving the deposition and retention of the ashes on a disk like sifting element while the latter is being rotated in a plane at a sufficient inclination to enable the ashes to run downwardly thereon.

Another object of the invention is the use of novel means for causing the continuous deposition of the ashes on the sifting element and preventing the escape thereof otherwise than through said element or through a restricted space adjacent the peripheral edge thereof.

Another object of the invention is the provision of novel means for detachably mounting a common pail for rotation in a partially inverted position above the sifting element whereby the latter may extend over the mouth of the pail in the manner of a closure, so that rotation of the pail may cause ashes contained therein to descend upon the element and be sifted thereby.

Another object of the invention is the provision of novel means for mounting and detachably clamping the pail for rotation in such partially inverted position and in operative relation to said sifting element.

Another object of the invention is the use of an ash can lid of novel design, having a centrally disposed hoodlike casing formed thereon, as a housing for mounting the pail in such rotary operative relationship to said sifting element.

Another object of the invention is to pro-

vide rotative means for imparting rotation to the pail through frictional engaging contact with the bottom thereof.

Another object of the invention is the provision of novel hinging means of hook-like form attached to the lid, which while permitting the latter to be bodily lifted and removed from the can, at the same time enable it to be turned and supported on the edge of the can in such open position relative to the latter as will permit the lifting and insertion of the pail within the casing of the lid in a vertical manner, and will enable the same to be completely mounted and locked in the casing while being supported therein in a substantially vertical upright position.

With the above and other objects in view, the nature of which will more fully appear as the description proceeds, the invention consists in the novel construction, combination and arrangement of parts as herein fully described, illustrated and claimed.

In the accompanying drawings, forming part of the application, similar characters of reference indicate corresponding parts in all the views.

Figure 1 is a central vertical sectional view of an embodiment of my invention, showing the pail mounted in operative position within the lid of the ash can.

Figure 2 is a similar view showing the lid turned back and supported in open position on the edge of the can with the sifting element thrown upwardly to its extreme position on the lid.

Figure 3 is a view of the lid partly in section showing the same as removed from the ash can with the sifting element lying within the body of the hood.

Figure 4 is a view of the sifting element, the arm carrying the same, and the locking link, shown as detached from the lid.

Figure 5 is a face view of the friction member employed for imparting rotation to the pail; and Figures 6 and 7 are views of modified forms of the sifting element.

The novel principle of sifting and separating ashes on which the present invention is based, may be broadly considered as involving the employment of the following essential devices, viz; first, a disk like sifting element of perforated or foraminous material centrally mounted for rotation in a plane at a sufficient inclination to enable ashes when deposited thereon to run down-

wardly over the upper face thereof; and second, a substantially cylindrical ash containing and feeding member superimposed upon the sifting element and mounted for 5 rotation thereover on an axis coinciding with the axis of rotation of the element, said member having at its lower end an open mouth adapted to be directly applied to the face of the element, and the element being 10 of sufficient extent to cover the mouth of the member in the manner of a closure. It will be apparent that by rotation of an ash containing member and sifting element thus formed and disposed, ashes contained within 15 in the member will be caused to descend downwardly upon the element and will tend to crowd against the lower portion of the face thereof, where through further rotation, the accumulated mass will be thoroughly agitated and all particles thereof brought rapidly into moving contact with the element, whereby the ash will be thoroughly separated and sifted, the finer consumed portions thereof dropping out and 20 escaping through the openings in the element, and the larger, unconsumed portions being salvaged and retained in the containing member. I have found that by this mode of operation, a sifting element of relatively small surface area may be very efficiently employed, and therefore in the embodiment of the invention herein illustrated and described, I avail myself of this principle of sifting ashes for bringing into use, 25 as an ash containing member adapted to function in connection with such sifting element, an article of general household use, viz; a common pail.

The invention additionally contemplates 30 the employment of suitable means for operatively mounting and rotating the sifting element and ash containing member in the desired inclined position, said means in the instant embodiment comprising an ash can 35 lid of suitable form, carrying clamping means for detachably locking the pail in rotary operative position therein, and an ash can whereon the lid is adapted to be supported in such a manner that the sifting element may lie immediately beneath the lid and directly over the mouth of the can, whereby the escape of ash dust may be effectually prevented and the apparatus thus rendered practically dustless in operation.

In the drawings the numeral 9 indicates 40 the ash can which is of the conventional type in general use, 10 indicates the lid for covering the can, and 11 indicates the pail which as shown, is of the common type having the usual bail, 12, for carrying the same. The lid 10 has a depending peripheral flange 13 for receiving the mouth of the can, and is provided with a flat peripheral body portion 14 adjacent the flange which is adapted 45 to lie over and closely engage the edge of

the can in order to seal the latter against the escape of dust. For conserving space within the can so that the same may be filled with the refuse portion of the ash to the fullest practical extent, I preferably provide 50 on the central portion of the lid an upstanding hood as 15, accessible from the lower side of the lid for the introduction and reception of the pail, the hood forming a casing of suitable interior conformation to 55 accommodate the pail when the latter is introduced therein in such manner as to occupy a partially inverted inclined position when the lid reposes over the can. It is contemplated to removably mount the pail 60 for rotary movement in such inclined position within the lid and at the same time lock the rotary sifting element which is indicated by the numeral 16 over the mouth thereof, the means employed to this end being preferably formed and disposed so as to act in the manner of a clamp, having members, one of which is the sifting element itself, for engaging and supporting the opposite ends of the pail.

Said means for mounting the bail include a short shaft 17, journaled in one side of the hood as in a bracket 18, carrying at its inner end a disk like friction block 19, of suitable diameter to be snugly received into the recess or depression 20, commonly formed at the lower end of the pail by the extension of the side walls customarily referred to as the chime. Said friction block is secured to the shaft in a simple manner, as by means of a pin 21, so that it may be rotated thereby, and the front face of the block is preferably made flat in order that it may frictionally contact an extended surface of the bottom of the pail to the end of enabling the rotary motion of the shaft to be thus imparted to the pail. As shown, the opposite end of the shaft is extended outwardly through a suitable perforation in the wall of the hood and is externally provided with a crank 40, 100 whereby it may be rotated.

On the side of the lid opposite the shaft is hingedly secured as by means of a perforated hinge member 22 attached to the wall of the hood, and a pin 23, an arm 24 adapted to swing in a vertical plane coinciding with the axis of the shaft, and on the side of said arm facing the shaft is mounted the sifting element 16. Preferably said element is made as shown of perforated sheet material in the form of a disk, although, as will be understood, the same may likewise be made of foraminous or reticulated material. Said element is mounted on the arm 115 24 for rotation about its centre by means of a reinforcing spider 25, having a central hub 26, through which passes a pivot pin 27 secured to the arm. The pin 27 extends toward the shaft 17 and is so disposed on the arm that the sifting element will rotate 120 130

thereon in a plane at right angles to the plane of movement of the arm, and the entire arrangement and location of the parts is such as to enable the sifting element to 5 be swung inwardly and brought squarely and centrally over the mouth of the pail when the latter is placed in the mounting with its bottom squarely resting on or against the friction block 19. Fingers as 10 projecting radially outward from the periphery of the sifting element, and preferably formed as extensions of the arms 29 of the spider 25, are adapted to engage over the edge of the mouth of the pail, and locking means, as an elongated link 30 pivoted to the free end of an extension 31 of the arm 24 and adapted for detachable engagement with a hook 32, are supplied for detachably locking the pail in operative position 15 between the friction block and the sifting element, the hook 32 being disposed on the side of the lid wherein the shaft 15 is journaled and being preferably formed as an integral part of the bracket 18. The shaft 17 is made of sufficient length to have a slight longitudinal play in the bracket 18 and is encircled by a spiral spring 43 interposed between the bracket and the friction block 19, the spring acting in an obvious 20 manner to retain the friction block and the sifting element in close frictional and supporting contact with the bottom and mouth of the pail respectively, while at the same time serving to retain the link 30 in locking engagement with the hook 32. The sifting element is preferably made of a diameter slightly less than the mouth of the pail so as to be received therein a limited distance, and the fingers 28 are slightly offset therefrom as at 33, providing shoulders 34 adapted to enter and engage the inner marginal edge of the pail, to afford supporting means therefor. With this arrangement as will be seen, rotary movement 25 may be imparted to the pail through the friction block 19, and transmitted to the sifting element through frictional contact of the edge of the pail with the fingers 28, whereby the pail and sifting element are adapted to be rotated in unison.

As previously stated, it is essential that the sifting element be arranged to rotate in a plane at a sufficient inclination to enable ashes to run downwardly thereon, and that the pail be likewise disposed at an inclination to secure the proper feeding and agitation of the ash. Inasmuch as in the present construction the friction element is designed to lie squarely over the mouth of the pail, and to therefore revolve in a plane at right angles to the longitudinal axis thereof, it will be apparent that the angles of inclination of the element and the pail are mutually interdependent, the one being controlled by the other. In practice I have

found that the best results may be obtained by disposing the parts so that these angles of inclination are at substantially forty-five degrees to the plane of the mouth of the ash can when the latter is standing in upright position, and in the present instance I adopt this arrangement, although I desire to have it understood that I do not confine myself thereto.

To avoid spilling the ashes while introducing and locking the pail in the clamping device, it is obviously essential that the pail be continuously held and maintained in a substantially vertical upright position throughout the entire mounting operation and until the sifting element is securely locked thereon, and it is one of the features of this invention to provide hinging and supporting means for the lid, which while permitting it to be lifted off and bodily removed from the can, at the same time render it capable of engagement with the edge of the can so that it may be turned upwardly and outwardly thereover and may be supported thereon in a suitable position to permit the vertical introduction of the pail into the hood. In my copending application for Letters Patent, Serial Number 416,254, filed October 11th, 1920, I show and claim a device for the accomplishment of a somewhat analogous purpose in connection with an ash sifting device, the same consisting of a member in the form of a hook of special shape; and in the present invention I preferably employ for this purpose a hook member 35 of the same general type as that herein described, differing therefrom only in details of construction. As shown, this hook member is formed as an integral part of the bracket 18, the bill 36 thereof being adapted to extend into the mouth of the can adjacent the marginal edge thereof when the lid is in closed position on the can. In conjunction with the hook member proper an arm 37 is provided, here shown as lying over the upper face of the adjacent peripheral portion of the lid and extending outwardly to the flange 13, which is adapted to impinge against the outer face of the can and act as a stop to limit the outward movement of the lid when the latter is swung upward to open position on the edge of the can. The shank of the hook 35 is transversely extended adjacent the bight thereof to provide a relatively wide bearing and purchase therefor over the edge of the can for the purpose of obviating the tendency of the lid when in open position to rotate sidewise and drop off of the can, and the arm 37 is made of sufficient strength and is so formed and disposed with relation to the bight of the hook as to securely support the lid in such an open position on the edge of the can as will permit the introduction of the pail in the lid in the requisite vertical

manner. It will be observed that when the lid is in such open position on the can, the body thereof lies in a plane at substantially the same angle to the plane of the mouth of the can as that occupied by the axis of the pail with respect to said plane when the lid is in closed position, which angle as previously stated is in the present instance substantially forty-five degrees; and it will further be seen that at this angle of the lid, the arm 24 bearing the sifting element 16 and link 30 may be swung upwardly and outwardly to a sufficient extent over the hinge 22 to enable said parts to be retained in their remote position by their own weight, thus permitting free and unobstructed access to the hood for placing the pail therein.

In operation, the pail, being portable, is filled with ashes from a stove or furnace and carried to the ash can. The lid of the can is then grasped by the handle 38 and turned back on the hinge member over the edge of the can to open position, and the arm 24 with the sifting element thereon is swung back out of the hood. The pail is then taken up by the bail and lifted into the hood, being placed in upright position on the friction block 19, where it will rest without further support. The arm 24 is now swung downwardly over the pail until the sifting element enters the mouth thereof with the fingers 28 engaging over the edge of the mouth when the arm is further pressed down a slight distance against the action of the spring 43 and the link 30 sprung into locking engagement with the hook 32. The lid with the pail thus completely mounted therein is now swung down over the mouth of the can, and the crank 42 turned to sift the ashes, rotary movement being imparted to the pail through the friction block 19, and transmitted from the pail to the sifting element through the fingers 28. After the ashes have been sifted, the apparatus is left to stand undisturbed for a sufficient period to enable the dust to become thoroughly settled in the can, when the lid is again opened and the pail with the reclaimed cinders therein removed.

In experimenting with this sifting device I have found that it is possible to use rotary sifting elements of a variety of different forms and shapes, some of which are attended with peculiar advantages in connection with special embodiments, and I have therefore shown several of these in the drawings as modifications of the preferred form herein described, the same, as well as all other equivalents, being embraced within the scope of the appended claims.

The modification shown in figure 6 represents a cone shaped sifting element adapted to lie completely over the mouth of the pail, having depending fingers 39 to retain it in operative position thereon, and that shown in

Figure 7 represents a sifting element of concavo-convex form. Both of these forms have the advantage of permitting the pail to be heaped with ashes to its fullest possible extent, though they are more expensive to manufacture and occupy more space in the lid and can than the flat type of element herein stated as preferred.

I may also state that I have found that the thorough and rapid cleansing of the cinders may be facilitated by preserving a slight or restricted space between the mouth of the pail and the periphery of the sifting element through which part of the consumed portion of the ash may pass, so that the sifting or separating process may take place as well immediately adjacent the inside face of the walls of the pail as at intermediate points in the mouth thereof, and I therefore, preferably adopt this construction in the present embodiment. I have also discovered that even an imperforate sifting element may be employed to good effect providing suitable space is allowed between the periphery thereof and the mouth of the pail, and while I have not shown such imperforate element, I suggest the same as an equivalent, and further suggest that the periphery of such element may be either circular in outline, or may contain indentations of various shapes.

An advantage attending the present form of ash sifter which should be noted, lies in the fact that the sifting element together with the arm on which it is mounted and the locking link, can be readily folded together into the body of the hood, and the entire apparatus thus be compactly cased for storing and shipping, the lid with the parts thus folded in being shown in Figure 3.

Having fully described my invention, I claim:—

1. In a sifting device, a rotatably mounted disk like sifting element adapted to be disposed for rotation in a plane at a sufficient inclination to enable the material to be sifted to run downwardly thereon, a material container in the form of a pail, and means for rotatably mounting said container in partially inverted position over and above said element.

2. In a sifting device, a rotatably mounted disk like sifting element adapted to be disposed for rotation in a plane at a sufficient inclination to enable siftable material to run downwardly over the face thereof, a container in the form of a pail, and means for mounting said container for rotation over and above said element on an axis substantially coinciding with the axis of said element.

3. In an ash sifting device, a pail, a rotatably mounted sifting element adapted to cover the mouth of the pail, and means for mounting and rotating the pail with the

- element in closed relation thereon at an axial inclination sufficient to enable siftable material therein to run downward by gravity over the inner face of the element.
4. The combination with an ash can, of a lid for covering the can, a disk like sifting element carried by the lid, a pail, and means for mounting the pail on the lower side of the lid for cooperative rotary sifting action with said element.
5. In an ash sifting device, the combination of an ash can, a lid for covering the mouth of the can, a pail, means for rotatably mounting the pail within the lid, and a disk like sifting element adapted to be rotatably interposed between the mouth of the pail and the mouth of the can.
6. In an ash sifting device, a pail, and means for detachably and rotatably mounting the pail, said means including a rotary disk like sieving element for adjustment over the mouth of the pail.
7. In an ash sifting device, the combination of an ash containing receptacle in the form of a pail having a flat bottom, and means for detachably mounting and axially rotating the receptacle in co-operative relation with a sifting element to sift the ashes therein, said means including a rotatably mounted disk applicable to the bottom of the receptacle to transmit rotary movement to the receptacle through frictional contact therewith.
8. In an ash sifting device, the combination of an ash containing receptacle in the form of a pail, and means for detachably mounting and axially rotating the receptacle to sift the ashes therein, said means including two rotatably mounted members applicable respectively to the bottom and the mouth of the receptacle, the member applicable to the bottom of the receptacle being designed for imparting rotary movement thereto, and the member applicable to the mouth thereof being designed for sifting the ashes therein.
9. In an ash sifting device, the combination with a removable lid for an ash can, of an ash containing receptacle in the form of a pail, and means associated with the lid for detachably mounting and axially rotating the receptacle under the lid to sift the ashes therein, said means comprising a rotatable member journaled through one side of the lid and adapted to be externally rotated and to be internally applied to the
- bottom of the receptacle for imparting rotary movement to the latter, an arm hinged internally to the lid opposite said member for swinging movement toward and from said member, a disklike foraminous sifting element rotatably mounted on said arm and adapted for clamping engagement over the mouth of the receptacle when said arm is swung toward said member, and means for detachably locking said arm in fixed relation to said member.
10. In an ash sifting device, the combination with a removable lid for an ash can, of an ash containing receptacle in the form of a pail, and means associated with the lid for detachably mounting and axially rotating the receptacle under the lid to sift the ashes therein, said means comprising a bracket secured to one side of the lid, a shaft rotatable externally of the lid journaled in said bracket and passing through the walls of the lid, a member adapted for frictional contact and supporting engagement with the bottom of the pail secured to the inner end of said shaft, an arm pivoted to the lid opposite said member for swinging movement toward and from the latter, a disklike foraminous sifting element rotatably mounted on said arm and adapted for supporting and closing engagement over the mouth of the receptacle when said arm is swung toward said member, and a resilient locking member on the free end of said arm adapted for co-operation with a corresponding locking member on the side of the lid adjacent said shaft for yieldingly maintaining the element in fixed clamping engagement over the mouth of the receptacle.
11. In an ash sifting device, the combination with an ash can and a removable lid for covering and sealing the mouth of the can, of means associated with the lid for removably mounting an ash containing receptacle thereunder for rotation on an axis at an angle to the plane of the lid, and a hinge member secured to the lid and adapted for engagement over the edge of the can to enable the lid to be turned over the edge to open position with respect to the can and to be supported and maintained thereon at an appropriate angle to permit the insertion and adjustment of the receptacle in a substantially vertical upright position in said mounting means.

In testimony whereof, I affix my signature.

FRANK H. LEHMAN.
